UNITED STATES PATENT OFFICE.

SIMEON HARTLEY, OF NEWARK, NEW JERSEY, ASSIGNOR TO THE NEWARK SHEET METAL WARE COMPANY, OF NEW JERSEY.

PIPE-FORMING MACHINE.

SPECIFICATION forming part of Letters Patent No. 449,412, dated March 31, 1891.

Application filed December 20, 1890. Serial No. 375,323. (No model.)

To all whom it may concern:

Be it known that I, SIMEON HARTLEY, a citizen of the United States, residing at Newark, in the county of Essex and State of New Jersey, have invented certain new and useful Improvements in Machines for Forming Leader-Pipes; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

The purpose of this invention is to provide a machine by means of which a piece of sheet metal provided on its longitudinal edges with the proper standing edges, when fed into said machine by the workman, is formed into a leader-pipe upon a mandrel adapted to be rotated in journals in the frame-supports of the machine, and the machine being provided with means for upsetting and interlocking the edges of the metal sheet, which can be readily and accurately done, producing in one operation a piece of sheet-metal pipe in which the seam has been formed and closed down without the use of solder, and, furthermore, a leader-pipe is the result which is of much greater length than such pipes as heretofore made.

The invention is further designed to secure a perfect union of the standing edges of the sheet metal, and also to provide a machine which can be readily and quickly adjusted to turn out leader-pipes of different sizes of diameters.

The invention is therefore further designed to provide a device or devices for regulating the sizes of the clamping or holding jaws and the formers, so that they will conform to the required size of the mandrel in making different-sized leader-pipes.

The form of construction selected to embody the invention in an operative machine is illustrated in the accompanying seven sheets of drawings, in which—

Figure 1 is a side elevation of my leader-forming machine. Fig. 2 is a horizontal section taken on line z in Fig. 1, illustrating one

form of mandrel considerably enlarged and its forming and clamping or holding jaws or arms. On Sheet 3, Fig. 3 is an end view of the left end of the machine; and Fig. 4 is a side view of said end shown in Fig. 3, certain parts thereon being represented in vertical section. On Sheets 4 and 5, Figs. 5 and 6 are vertical sections taken through lines x and y , respectively, in Fig. 1. On Sheet 6, Figs. 7, 8, 9, and 10 are views illustrating the several operations or steps in the process of forming the pipe and in the bending down and interlocking of the seam. On Sheet 7, Figs. 11 and 12 are a front and side elevation, respectively, of the device for firmly closing down the seam after the ends of the sheet metal have been interlocked, said device being geared in engagement with a rack in line with and directly above the mandrel and the seam in the pipe which has been formed upon said mandrel. In Figs. 13 and 14 are illustrated adjusting devices adapted to be attached to the formers and to the clamping-jaws when a mandrel of smaller diameter is used than that shown in Figs. 1, 2, *et seq.* Fig. 15 is a front view of a part of the forming-bar used in connection with the construction illustrated in Fig. 14.

In the above-described views similar letters of reference are employed to indicate corresponding parts in each of the several figures.

The construction and operation of the leader-pipe-forming machine will now be described, in order that a more complete understanding may be had of the relation of the several improvements shown in the drawings.

The machine consists of two main frame-supports A and A' , which are preferably formed as shown in Figs. 3, 4, 5, and 6, and upon which are arranged and secured the heads a and a' , each of which is provided with a journal-bearing a^2 and a^3 , respectively, said bearings being open at the top and having placed therein a mandrel B , which is provided along its length on one side with a steel plate b , secured to said mandrel by means of screws or pins, and which plate is made to project upwardly at its forward end b' , forming a longitudinal recess or slot b^2 along the entire length of the mandrel between the latter

and said plate and between the frame-supports A and A', as will be evident from Figs. 3, 5, 6, 7, 8, 9, and 10.

The mandrel B is loosely arranged in its bearings, and on one end of the machine it projects considerably beyond the bearing in the frame-support A, being provided with an operating lever or handle b³ and a locking or holding device C, which is attached to the frame A, and said end of the mandrel also passing through a frame or gallows A², the purpose of which will be described herein-after. Upon each of the heads a and a' are secured the supports a⁴ and a⁵, respectively, each of which has in its upper end a screw a⁶, provided with the nuts a⁷ and a⁸ for securing in position under the frame-supports A and A' the cross-bar A³. The lower ends of the frames A and A' are secured by a tie-bolt A⁴. This arrangement constitutes the main frame of the machine. From Fig. 2 it will be evident that the mandrel is maintained in the proper position in its bearings by means of collars a⁹ and a¹⁰, and upon the mandrel on the outside of said collar a¹⁰ is arranged the locking or holding device C, which consists of a wheel c, secured to the mandrel in any manner and provided with a recess c', which, when the mandrel is in its normal position, stands upwardly in a vertical plane passing through the central longitudinal axis of the mandrel. On one side of the frame A is secured a plate c², provided with ears or lugs c³, between which is pivoted a handle c⁴, as will be noticed from Figs. 1, 2, and 3. Said handle has on its under side a downwardly-projecting lug c⁵, which drops into the recess c' in the wheel c, and thereby holds the mandrel in its normal position, so that the edge b' of the plate b, secured to said mandrel, is in the same vertical plane, passing through the central longitudinal axis of the mandrel, or nearly so. In this same vertical plane, directly beneath the mandrel, is arranged a shaft D, upon which are secured formers E and two sets of clamping or holding arms, which, however, are loosely arranged on said shaft, and which are employed in the several steps during the process of forming the sheet metal into a leader-pipe, &c. Said shaft D, as will be seen more especially from Fig. 1, is arranged in the bearings a¹¹ and a¹² in their respective supports A and A', and is secured therein by means of suitable collars d. On the other end of said shaft is arranged an operating lever or handle d', adapted to slide against the flat surface d² of a curved plate d³, adjustably secured to a support d⁴, attached by means of a foot d⁵ on the frame A. Said plate d³, as will be seen from Fig. 4, is secured by means of bolts d⁶ and d⁷ in slots d⁸ and d⁹ in the support. The top of this support is bent at a right angle, and so is the plate d³, and a stud d¹⁰, centered in the top of said bent portion of the support and working through a threaded perforation in the bent portion of the plate d³, serves, when

turned, to cause said plate to be adjusted upon its supports, the bolts d⁶ and d⁷ sliding within the slots d⁸ and d⁹. The plate d³ is also provided with a hole d¹¹, as will be seen from Fig. 3, and when the shaft D has been turned by means of the lever d', the hooked end d¹² of the arm d¹³ slides against the surface d² until it drops into the hole d¹¹, and the shaft is thus locked in the proper position. Said arm d¹³ is pivoted between lugs d¹⁴ on the lever d', and a spring d¹⁵ causes the opposite end d¹², which passes through a perforation in the lever d', to be constantly forced against the surface d², as will be evident from Fig. 4.

Of course it will be understood that when mandrels of different diameters are used the hole d¹¹ is adjusted accordingly by means of the stud d¹⁰.

The operation of the machine in forming leader-pipes from sheet metal is as follows: A piece of sheet metal g of the proper width, and which has been previously provided with the projections g' and g², is placed over the edge b' upon the mandrel B, so that the edge g' is caught under the plate b in the recess b², as is clearly illustrated in Fig. 7. As shown in said figure, the formers E are then brought into their proper positions. The construction of said formers is illustrated more especially in Figs. 1 and 2, and consists of any desirable number of peculiarly-shaped arms e, which are slipped upon the shaft D and keyed thereon in certain positions, as will be noticed from said figures. Said arms e are arranged upon their shaft D so that they project upwardly, and are provided with a semicircular portion e', which is of a slightly-increased diameter over that of the mandrel B. As will be seen more especially from Figs. 3 and 5, said arms e are provided with straight portions e², to which, as will be seen from said figures, and also from Figs. 1 and 2, is secured an adjustable depressor-bar H, the use and operation of which will be described farther on. Now when the former-arms e have been brought into the position indicated in Fig. 7, by turning the shaft D by means of its handle or lever d' and then locking it by the forcing of the end d¹² on the arm d¹³ into the hole d¹¹ on the curved plate d³ the pivoted handle c⁴ on the locking device C is thrown back, releasing the tooth or projection c⁵ from engagement with the recess c' in the wheel c. The mandrel B is then turned by means of its handle b³, making one complete turn, the upper edge of the sheet metal sliding against the lower edge h of the depressor-bar H and in the circular portions e' of the former-arms, and during the several positions as the sheet metal is being wound around the mandrel the clamping-arms F are forced up against the metal sheet, and when the sheet metal has been still further wound around the mandrel, assuming the position shown in Fig. 8, then a second set of clamping-arms F' on the oppo-

site side of the machine are brought to bear against the sheet metal. Said clamping or holding arms F, as will be seen from Figs. 1 and 6, consist of a number of arms f, loosely arranged by means of sleeves f' on the shaft D. They are provided with oppositely-projecting portions f² and f³, said portions f³ being connected by a straight bar f⁸ and operated by a hand-lever f¹⁰, whereby the portions f², provided with the recesses f⁶, can be firmly held against the metal sheet during the process of forming the leader-pipe. The clamping-arms F' are similar in their construction and action to the arms F, and they consist of the arms f⁷, also loosely arranged on the shaft D by means of the sleeves f⁹. A bar f⁴ connects the arms f⁷, which can be operated by the levers f⁵ at either end of the bar f⁴. Said levers are in close contact with the inner sides i of the standards I, and, as is clearly shown in Fig. 3, bear against a pin i', which limits the downward movement of said levers. Said standards are made adjustable by providing the main portion with a bolt i², which extends through a slot i³ in the plate i⁴, whereby said plate is made adjustable and can be raised or lowered when desired. Now when the sheet metal has been formed, as shown in Fig. 8, it will be noticed that the end g² of the sheet projects up beyond the lower edge h of the depressor-bar H. Said bar is secured to the former-arms e by means of screws or bolts h' or other means arranged in the inclined slots h², as will be seen from Figs. 1, 2, and 3. A post h³ is secured to a short bar h⁴, (see Fig. 1,) connecting two of the arms e, and upon the upper end of said post I have arranged a pivoted lever J, provided at one end with a handle portion j and at the other end with a slotted eye j', which is arranged in such a manner that it almost rests upon the upper surface h⁵ of the depressor-bar H, and a pin h⁶ on said bar projects through the slot in the lever J, as will be evident from said Figs. 1 and 2.

The next step in the operation of forming the leader-pipe is the forcing down of the end g² of the metal sheet so that it will assume the position indicated in Fig. 9. This is accomplished by turning the lever J toward the operator, which causes the slotted portion j' to slide on the pin h⁶, forcing the depressor-bar h down along the slots h², as will be clearly understood from Fig. 2. At the same time the lower edge h of the bar is brought down and bears tightly against the end g² of the sheet metal, bringing said end of the metal down upon the mandrel B, and the next step in the operation, as will be seen from Fig. 10, is to turn the mandrel in the opposite direction, so that the end g' of the sheet metal will be withdrawn from its holding engagement with the longitudinal slot or recess b² in the mandrel. By slightly loosening the clamping-arms F' said end g' of the sheet metal will spring up far enough to allow the end g² to be forced under the same, by tightly forcing the formers E and the depressor-bar H up

against the mandrel, whereby said ends g' and g² will interlock, as clearly shown in said Fig. 10. This having been accomplished, the formers and clamping arms or jaws are released and thrown off, and the joint or seam in the pipe just formed is tightly closed down by means of the bending-down device. (Illustrated in detail in Figs. 11 and 12.)

To more fully understand the construction and operation of this bending-down mechanism, I will now describe the construction of the same and its arrangement upon the cross-bar A³ of the machine and the manner in which the same is operated to move from one end of said bar to the other end. Said bar A³, as will be noticed from the cross-section of the same in Fig. 12, is provided with two oppositely-arranged chamfered projections, forming ways or guides a¹³ and a¹⁴, respectively, against the under sides a¹⁵ and the chamfered sides a¹⁶ of which I have arranged the small plates l and l' of the bending-down device. Said plates are secured in position on these ways or guides by means of top pieces l², which are secured to the plates l and l' by bolts or screws l³, and the ends l⁴ thereof project over upon the upper surfaces of the guides, whereby the device can be caused to move upon said ways, as will be seen. One of said pieces l² is provided with a bearing l⁵, in which is arranged a spindle l⁶, provided with a pinion m and a hand-wheel n. Said pinion meshes with a gear-wheel m' on a spindle or shaft m², secured in the bearings l⁷ and l⁸ on the plates l and l', respectively. As will be seen more particularly from Figs. 11 and 12, said plates l and l' project down on opposite sides of the rack a¹⁷, secured on the underside at its ends to the cross-bar A³ by bolts a¹⁸. A pinion m³ on the spindle m² meshes with the teeth on this rack. On opposite sides of this pinion m³ are arranged the crank-arms m⁴ and m⁵, provided at their lower ends with a bolt or pin o, on which is arranged a wheel o', provided around its circumference with the groove o². From one of said arms, as m⁴, extends a handle p, which is normally held in its raised position by a spring p', attached to a post p² on the plate l. Said lever and its spring tend to throw the wheel o' normally out of the way of the movement of the mandrel B. When, however, the joint or seam has been formed and the formers and clamping-arms have been thrown back, then lever or handle p is pressed down by the operator, so that the groove o² in the wheel o' is in close contact with the open seam on the pipe just formed. By bearing down on the lever p and turning the hand-wheel n pinion m operates the gear m' and its spindle m², causing the pinion m³ to engage with the teeth of the rack on the cross-bar A³, the whole device thus being caused to move along the guides or ways thereon, while the wheel o' revolves along the seam in the pipe upon the mandrel and tightly closes down the seam therein. When this has been done, said bending-down

device is returned to its former position, as indicated in Fig. 1. The finished pipe is now ready to be removed from the mandrel. In order to do this, the end B' of the mandrel is raised from its bearing a^3 , lifting the mandrel on the bearing a^2 as a fulcrum. This lowers the opposite end B² of the mandrel within the standard or gallows A², and by placing an ordinary wedge-shaped wooden block upon said end of the mandrel and forcing it under the pin A⁵ in said gallows A² the mandrel is retained in an inclined raised position and the completed leader-pipe can be drawn therefrom at the raised end B', as will be understood.

In order to prevent any sagging of the shaft B when used in machines to make very long pieces of sheet-metal pipes, I have arranged beneath the mandrel, as shown in Fig. 1, a support R, which can be adjusted to the proper height to keep the shaft perfectly level. It consists, mainly, of a supporting-plate r and a rod r', which screws into a base r² and is provided with a nut r³ for adjusting the same when necessary.

The construction in the machine described in the above is for producing leader-pipes of the largest diameter now in use; but by changing the proportions of the several parts of the machine it will be practical for forming pipes of any diameters. The same machine, however, can be employed for making pipes of smaller diameters by using smaller mandrels in connection with the herein-described formers and clamping jaws or arms; but in this case the formers and clamping-jaws are provided with an adjusting means.

By removing the boxes or bearings a^2 and a^3 and replacing them by suitable boxes which fit the mandrel of smaller diameter, and in order that the present formers and clamping-arms will be suitable to such smaller mandrel, I secure within the curved recesses e' of the arms e, by means of bolts, blocks s, which conform with the proper diameter of the mandrel upon which the smaller size of pipe is to be formed. In the same manner the clamping-arms are provided with similar blocks s' and s², as will be seen from Fig. 13. The operation of the machine in forming this pipe will be precisely the same as that described in connection with Figs. 1, 2, &c.

In making pipes of very small diameters it may be necessary to widen the depressor H. This is accomplished, as will be seen from Figs. 14 and 15, by attaching to said bar, by bolts, blocks t, which are connected by a bar t', which operates upon the end g' of the metal sheet, instead of the edge h, as in the construction described in the above.

It will be understood that many variations of construction and arrangements of the various parts herein described may be made without departing from the scope of my invention. Hence I do not wish to be limited to the exact form of mechanism shown and described. For instance, the formers and

clamping-arms can each be arranged on and worked by means of separate shafts and the machine still be operative, and other changes may be made in other parts of the mechanism of the machine.

Having thus described my invention, what I claim is—

1. In a machine for forming leader-pipes, the combination of a mandrel removably arranged in bearings in the supports of the machine, formers for bending the metal sheet around the mandrel, clamping or holding jaws on either side of said mandrel, said formers and clamping or holding jaws being arranged on the same shaft, arranged in the same vertical plane, passing through the central axis of the mandrel, but each being independent in its action from the other, said formers being keyed to said shaft and operated thereby, while said clamping or holding jaws rotate loosely on the same shaft, said clamping or holding jaws being provided with handles for forcing them against the sheet metal being formed on the mandrel, and a bending-down device to close the joint in the leader-pipe, all of the operations of said forming, clamping, and bending-down devices following consecutively without removing the metal sheet from the machine, for the purposes set forth.

2. In a machine for forming leader-pipes, the combination of a mandrel removably arranged in bearings in the supports of the machine, formers for bending the metal sheet around the mandrel, clamping or holding jaws on either side of said mandrel, a depressor-bar working in slots in said formers provided with means for depressing the same, said formers and clamping or holding jaws being arranged on the same shaft but each being independent in its action from the other, and a bending-down device to close the joint of the leader, all of the operations of said forming, clamping, depressing, and bending-down devices following consecutively without removing the metal sheet from the machine, for the purposes set forth.

3. In a machine for forming leader-pipes, the combination of a mandrel provided with a slot extending longitudinally therein, into which the sheet metal is inserted and said mandrel being removably arranged in bearings in the supports of the machine, formers for bending the metal sheet around the mandrel, clamping or holding jaws on either side of said mandrel, said formers and clamping or holding jaws being arranged on the same shaft, arranged in the same vertical plane, passing through the central axis of the mandrel, but each being independent in its action from the other, said formers being keyed to said shaft and operated thereby, while said clamping or holding jaws rotate loosely on the same shaft, said clamping or holding jaws being provided with handles for forcing them against the sheet metal being formed on the mandrel, and a bending-down device to close the joint of the leader-pipe,

all of the operations of said forming, clamping, and bending-down devices following consecutively without removing the metal sheet from the machine, for the purposes set forth.

- 5 4. In a machine for forming leader-pipes, the combination of a mandrel provided with a longitudinal slot into which the sheet metal is inserted and said mandrel being removably arranged in bearings in the supports of the machine, formers for bending the metal sheet around the mandrel, clamping or holding jaws on either side of said mandrel, said formers and clamping or holding jaws being arranged on the same shaft, arranged in the 15 same vertical plane, passing through the central axis of the mandrel, but each being independent in its action from the other, said formers being keyed to said shaft and operated thereby, while said clamping or holding 20 jaws rotate loosely on the same shaft, said clamping or holding jaws being provided with handles for forcing them against the sheet metal being formed on the mandrel, a bending-down device to close the joint in the 25 leader-pipe, all of the operations of said forming, clamping, and bending-down devices following consecutively without removing the metal sheet from the machine, means for turning said mandrel in its bearings, and a 30 holding or locking device for locking the mandrel in the desired position, for the purposes set forth.

5. In a machine for forming leader-pipes, the combination of a mandrel provided with 35 a longitudinal slot into which the sheet metal is inserted and said mandrel being removably arranged in bearings in the supports of the machine, formers for bending the metal sheet around the mandrel, clamping or holding 40 jaws on either side of said mandrel, said formers and clamping or holding jaws being arranged on the same shaft, arranged in the same vertical plane, passing through the central axis of the mandrel, but each being independent in its action from the other, said formers being keyed to said shaft and operated thereby, while said clamping or holding 45 jaws rotate loosely on the same shaft, said clamping or holding jaws being provided with handles for forcing them against the sheet metal being formed on the mandrel, a bending-down device to close the joint of the 50 leader-pipe, all the operations of said forming, clamping, and bending-down devices following consecutively without removing the metal sheet from the machine, means for turning said mandrel in the bearings, and a holding or locking device for locking the 55 mandrel in the desired position, and means on the shaft upon which the formers and clamping devices are arranged, engaging with a handle or lever on said shaft for locking or holding the same in the desired position, for the purposes set forth.

6. In a machine for forming leader-pipes, the combination, with a slotted mandrel provided with a locking mechanism on one end

thereof consisting, essentially, of a slotted wheel and a toothed lever pivoted to one of the mandrel-supports, of formers secured to a shaft provided with means for rotating the same, said formers having upwardly-projecting portions to which is secured a depressor-bar adapted to force the sheet metal down upon the mandrel, as and for the purposes set forth.

7. In a machine for forming leader-pipes, the combination, with a slotted mandrel, of formers secured to a shaft provided with means for rotating the same, said formers having upwardly-projecting portions to which is secured a depressor-bar by means of pins or bolts working in slots in said bar, and a handle pivoted between two of said former-arms to operate said bar, whereby the latter receives a downwardly-inclined movement, for the purposes set forth.

8. In a machine for forming leader-pipes, the combination, with a slotted mandrel, of formers secured to a shaft provided with means for rotating the same, said formers having upwardly-projecting portions to which is secured a depressor-bar by means of pins or bolts working in slots in said bar, and a handle pivoted between two of said former-arms to operate said bar, whereby the latter receives a downwardly-inclined movement, and means on said handle on the former bearing-shaft for locking the same in the desired position, for the purposes set forth.

9. In a machine for forming leader-pipes, the combination, with a slotted mandrel loosely turning in bearings and adapted to be removed therefrom, and a shaft arranged in the same vertical plane passing through the central axis of the mandrel and permanently secured in the supports of the machine, of forming and clamping devices on said shaft, each working independent of the other and each constructed and arranged to form the sheet metal around the mandrel and hold the same thereon and cause the edges of said metal to interlock, said formers being keyed to said shaft and operated thereby, while said clamping or holding jaws rotate loosely on the same shaft, said clamping or holding jaws being provided with handles for forcing them against the sheet metal being formed on the mandrel, and a bending-down device arranged and working on a rack in the machine directly above the mandrel, said device being adapted to move along said rack and engage with the seam formed in the leader-pipe, whereby said seam is closed down, for the purposes set forth.

10. In a machine for forming leader-pipes, the combination, with a slotted mandrel arranged in bearings in the supports of the machine, a cross-bar A³, connecting said supports and formers and clamping or holding devices, and a depressor-bar secured to said formers for forming the leader-pipes around the mandrel and causing the edges of the sheet metal to interlock, of means constructed and

arranged to be moved along the rack on said cross-bar and engage with the seam formed in the pipe, whereby said seam is tightly closed down, for the purposes set forth.

- 5 11. In a machine for forming leader-pipes, the combination of a mandrel arranged in bearings in the supports of the machine, formers for bending the metal sheet around the mandrel, clamping-jaws on either side of said mandrel, a depressor-bar working in slots in said formers and provided with means for depressing the same, said formers and clamping-jaws being arranged on the same shaft, and a slotted wheel on said mandrel, and a toothed 15 lever pivotally attached on one of said supports adapted to engage with said wheel to hold the slotted mandrel in its normal and inoperative position, as and for the purposes set forth.
- 20 12. In a machine for forming leader-pipes, the combination, with the mandrel B, of shaft D, formers E, and a lever for operating said shaft provided with a spring-actuated and pivoted arm, one end of which passes through 25 a perforation in said lever and is adapted to engage with a hole in a plate adjustably secured in a support on one of the machine-supports, for the purposes set forth.
- 30 13. In a machine for forming leader-pipes, the combination, with mandrel B, shaft D, formers E, and a lever d' for operating shaft D, and a spring-actuated arm pivotally secured to said lever d' , of a plate d^3 , adjustably secured by means of bolts in slots in a 35 support d^4 , and the end d^{12} of the arm on lever d' being adapted to engage with a perforation in said plate d^3 , for the purposes set forth.
- 40 14. In a machine for forming leader-pipes, the combination, with the mandrel B and shaft D, of formers E, consisting of arms e , secured on said shaft, provided with recessed portions e' , adapted to embrace the mandrel, said arms e being provided at their upper ends with an adjustable depressor-bar, and means secured 45 between two of said arms e on a connecting-piece for adjusting said depressor-bar, as and for the purposes set forth.
- 50 15. In a machine for forming leader-pipes, the combination of a mandrel, with formers, holding or clamping jaws, and a depressor-bar adjustable in relation to each other to form the sheet metal around the mandrel, and curved plates adapted to be secured within the curved portions of the said formers, and 55 clamping-jaws, whereby they are made to fit a variety of such mandrels, for the purposes set forth.
- 60 16. The herein-described machine for forming leader-pipes, consisting, essentially, of two supports A and A', provided with heads a and a' , having removable bearings therein, a recessed or slotted mandrel removably arranged in said bearings, a slotted wheel secured on said mandrel in locking engagement with a toothed lever pivoted on said support A, and a handle on said mandrel for operating the

same when said toothed lever has been released from the holding engagement with said slotted wheel, a shaft B, supported in bearings in said frame-supports A and A', operated by means of a handle, and means thereon for locking said shaft in the desired position, formers keyed on said shaft, and two sets of clamping arms or jaws loosely arranged on said shaft, but operating independently by 70 means of handles, a depressor-bar H, secured to said formers, as set forth, all of the operations of said formers, clamping-arms, and depressor following consecutively and bending the sheet metal into form and interlocking the 75 edges and forming a seam, a cross-bar A³, connecting supports a^4 and a^5 on the frames A and A', respectively, said bar being provided on opposite sides with ways or guides and on its under side with a rack, and a bending-down 80 device sliding on said ways, being provided with gear mechanism for operating a pinion in engagement with the teeth on said rack and having a wheel operated by spring-actuated lever to cause the same to be depressed upon 85 the seam of the pipe and rotate thereon as said bending-down device moves forward on the cross-bar A³, whereby said seam is firmly closed down, and a support or gallows A² at one end of the machine, provided with a pin 90 A⁵ for the insertion of a wedge between said pin and the mandrel, whereby the latter can be held in an inclined position for the removal of the completed leader-pipe from the raised end of the mandrel, as and for the purposes set forth.

17. In a machine for forming leader-pipes, the combination, with the mandrel B and shaft D, of formers E, consisting of arms e , secured on said shaft and provided with recessed portions e' , adapted to embrace the mandrel, said arms e being provided with an adjustable depressor-bar, and arms F, loosely arranged on said shaft D and connected by a bar f^8 , and handles f^{10} for operating the same 110 and causing the curved ends of the arms F to clamp the sheet metal on the mandrel, for the purposes set forth.

18. In a machine for forming leader-pipes, the combination, with the mandrel B and shaft D, of formers E, consisting of arms e , secured on said shaft and provided with the recessed portions e' , adapted to embrace the mandrel, said arms e being provided with an adjustable depressor-bar, and a clamping device F', comprising therein arms f' , loosely arranged on said shaft D and connected by means of a bar f^4 , provided with levers or handles f^5 , as set forth.

19. The combination, in a machine for forming leader-pipes, with the mandrel B and the shaft D, of a clamping device F', comprising therein arms f^7 , loosely arranged on the said shaft and connected by means of a bar f^4 , provided with handles or levers f^5 , said handles being in close sliding contact with standards or frames I, provided with a pin i' , where-

by the levers and the clamping device can be held in a desired position, as and for the purposes set forth.

20. The herein-described machine for forming leader-pipes, consisting, essentially, of two supports A and A', provided with heads a and a', having removable bearings therein, a recessed or slotted mandrel removably arranged in said bearings, a slotted wheel secured on said mandrel in locked engagement with a toothed lever pivoted on said support A, and a handle on said mandrel for operating the same when said toothed lever has been released from its holding engagement with said slotted wheel, a shaft D, supported in permanent bearings in said frame-supports A and A', operated by means of a handle, and means thereon for locking said shaft in a desired position, formers keyed to said shaft, and two sets of clamping arms or jaws loosely arranged on said shaft, but operating independently by means of handles, a depressor-bar H, secured to said formers, as set forth, all of the operation of said formers, clamping-arms, and depressor following consecutively and bending the sheet metal into form and interlocking the edges and forming a seam, a cross-bar A³, connecting supports a⁴ and a⁵ on the frames A and A', respectively, said bar being provided on opposite sides with ways or guides and on its under side with a rack, and a bending-down device sliding on said ways, being provided with gear mechanism for operating a pinion in engagement with the teeth on said rack and having a wheel operated by a spring-actuated lever to cause the same to be depressed upon the seam in the pipes and rotate thereon as said bending-down device moves forward on the cross-bar A³, whereby said seam is firmly closed down, as and for the purposes set forth.

21. In a machine for forming leader-pipes, the combination, with a mandrel adapted to rotate in bearings and upon which the leader-pipe is formed, its supports, and the cross-beam A³, provided with ways or guides on

opposite sides and a rack on its under side, of a bending-down device adapted to slide on said ways and provided with a depressible seam-closing wheel, as and for the purposes set forth.

22. In a machine for forming leader-pipes, the combination, with the mandrel B, the cross-beam A³, provided with ways or guides on opposite sides and a rack on its under side, of a bending-down device consisting of plates l and l', secured to the guides by plates l², a pinion m on one of said plates operated by a hand-wheel n, said pinion engaging with a gear-wheel m' on a spindle m², provided with a pinion m³, meshing with the teeth of the rack, arms m⁴ and m⁵ on said spindle provided with a seaming-wheel o', having a groove in its circumference, and a spring-actuated handle p, secured to one of said arms for depressing said seaming-wheel upon the interlocked edges of the sheet-metal pipe and firmly closing the seam, as and for the purposes set forth.

23. In a machine for forming leader-pipes, in combination with a mandrel adapted to rotate in bearings and upon which the leader-pipe is formed, its supports, and the former-arms e, a plate s, secured in the curved recess e' of each arm by means of a bolt, as and for the purposes set forth.

24. In a machine for forming leader-pipes, the combination, with a mandrel and a shaft D, of formers provided with a depressor-bar H, a bar t, secured thereto by means of blocks t', said formers consisting of arms e, to which said depressor-bar is adjustably secured, and means connected with said depressor-bar for adjusting the same, as and for the purposes set forth.

In testimony that I claim the invention set forth above I have hereunto set my hand this 13th day of December, 1890.

SIMEON HARTLEY.
